UNITED STATES PATENT OFFICE.

MURRAY CHEEVER, OF BOSTON, MASSACHUSETTS, ASSIGNEE TO THE
E. HOWARD CLOCK COMPANY, OF BOSTON, MASSACHUSETTS, A
CORPORATION OF MAINE.

ELECTROMAGNETIC MOTOR.

No. 818,775.

Specification of Letters Patent.

Patented Feb. 27, 1906.

Application filed February 20, 1905. Serial No. 246,423.

To all whom it may concern.

Be it known that I, MURRAY CHEEVER, of Boston, in the county of Suffolk and State of Massachusetts, have invented certain new and useful Improvements in Electromagnetic Motors, of which the following is a specification.

This invention relates to motors in which an interrupted current of electricity is supplied to an electromagnet for producing intermittent motion in an armature from which driving connections extend to a driven mechanism of any kind.

The object of the present invention is to provide an apparatus of this character capable of operating the hands of a clock by which the required amount of motion may be given to the driven mechanism by a relatively small motion of the armature and requiring, consequently, a less expenditure of electrical energy and less powerful batteries or other devices for supplying electromotive force than are required by motors of this character now in use.

The invention particularly consists in an arrangement of levers connected to the armature of an electromagnet and suitably arranged to operate a rotating driven mechanism by which the movement of the connection which operates the driven mechanism is varied in proportion as the strength of the magnetic attraction on the armature varies with changes in the distance between the armature and the poles of the magnet, the details of which I will now proceed to describe and claim, reference being had to the accompanying drawings, in which—

Figure 1 represents an elevation of an apparatus constructed in accordance with my invention, showing the driven shaft in section. Fig. 2 represents a fragmentary elevation showing the parts comprised between the arrows of line 2-2 in Fig. 1 as seen looking in the direction of the arrows. Fig. 3 represents a corresponding elevation as seen looking in the direction of the arrows of line 3-3 of Fig. 1. Figs. 4 and 5 represent, respectively, sectional views taken on line 4-4 and 5-5 of Fig. 1.

The same reference characters indicate the same parts in all the figures.

1 represents an electromagnet having pole-pieces 2 3, adjacent to which is located an armature 4, adapted to be moved toward the

pole-pieces by magnetic attraction when a current of electricity is supplied to the electromagnet. The magnet is suitably attached to a frame consisting of the side pieces 5 6 and posts 7, the side pieces also containing pivots 8 9 10, upon which are rotatably mounted levers 11 12 and a pawl 13. The armature is connected to one of the levers, so as to move the same when it is itself moved toward or away from the magnet, the preferred connection being that illustrated in the drawings, wherein the armature is shown as being carried by the arm 14 of lever 11. The other arm of this lever extends adjacent to and substantially parallel with the other lever 12, having one of its sides or edges 15 in engagement with the adjacent edge 16 of lever 12, the latter lever being retained in engagement with the lever 11 by a spring 17, held at one end by a collar 18 on the post 7, its other end being suitably engaged with lever 12. A preferred construction by which this engagement may be made is more particularly illustrated in Fig. 4, which shows a hole 181, extending through a protuberance 19 on the lever, through which the end of spring 17 is passed. The length of the hole is such that the spring engaging the opposite ends thereof on opposite sides of the axis is enabled to hold the lever in the position shown in Fig. 1 and resist movement thereof away from lever 11, while at the same time permitting movement under the influence of a force strong enough to bend the spring.

Near its free end lever 12 has pivoted to it at 20 a pawl 21, which is adapted to engage the teeth of a ratchet-wheel 22, which is fast upon a shaft 23. The ratchet-wheel and shaft constitute the driven mechanism by which motion is communicated to any desired apparatus, such as the hands of a clock, for this device is particularly intended as a clock mechanism, although of course it is capable of being applied to operate any other mechanism whatever.

The construction and arrangement is such that the point of engagement of the levers being on the side of the pivot opposite to the armature when the latter is moved toward the magnet lever 12 is moved in opposition to the stress of spring 17 to withdraw pawl 21 from the tooth of the ratchet with which it is engaged. When the device is so operating, pawl 13 is caused to engage the ratchet and

prevent retraction of the same, the pawl being so arranged as to tend under the influence of gravity to engage the ratchet; but there is also provided a means by which positive engagement may be insured, this means consisting of an arm 24, rigidly connected to lever 12 and carried around lever 11 above and in close proximity to the free end of pawl 13. When the lever 12 is retracted, this arm withdraws and engages the upper surface of pawl 13, holding the same in contact with a tooth. This arm is raised when being retracted and when moved far enough engages the under surface of pawl 21, holding the latter elevated. It may be arranged at any desired height, so as to hold the pawl away from the ratchet until a predetermined time, and thus it may allow the pawl to fall into engagement with the ratchet behind the next succeeding tooth and prevent it engaging with the second tooth or any one farther removed from that with which the pawl is engaged in its advanced position, or it may be arranged to allow the pawl to engage any of the teeth within the limits of its motion.

25 is a stud mounted upon the side piece 5 adjacent the end of pawl 21 and adapted to be engaged by an inclined surface 26 on this pawl when the latter is advanced. The inclined surface causes the pawl to be forced by the stud into positive engagement with a tooth of the ratchet and also holds the pawl in such engagement, preventing it from being raised and so locking the ratchet against movement in either direction by the application of any external force.

It will be observed that the side 15 of lever 11 which engages lever 12 is curved and that when the armature is separated most widely from the poles of the magnet the point of engagement between the levers is near the free end of 12 and near the fulcrum of 11, while the levers are out of engagement during the remainder of their lengths. As lever 11 is turned about its pivot the point of engagement between itself and the other lever will be shifted away from its pivot and toward the pivot of lever 12, the side 15 rolling upon the side 16 of lever 12 and at the same time forcing the latter lever to the left in opposition to the pressure of spring 17. Thus as these levers are successively moved the arm of lever 11 which engages lever 12 continually becomes longer, while the arm of lever 12 between its point of engagement with lever 11 and its pivot becomes correspondingly shorter, it being understood that during this motion the armature is being moved toward the magnet, the direction of shifting of the point of engagement being reversed when the armature is moving away from the magnet. Thereby for equal intervals of motion of the armature toward the magnet the movement of the end of lever 12 is increased—that is, a much greater amount of movement is given

lever 12 when the armature is nearest the magnet than when it is most distantly removed. This arrangement is provided for the reason that the attraction of the magnet for the armature varies with differences in the distance, being inversely proportional to the squares of the distances between the magnet and armature, and the shapes of the engaging surfaces of the two levers are such that the greatest portion of the work required to move the lever 12 against the tension of its spring a sufficient amount to cause the pawl to engage a subsequent tooth is performed by lever 11 when the armature is nearest the magnet. The spring exerts a resistance of constant force, while the force of the magnet is comparatively slight when the armature is at its greatest distance from the magnet and increases as the armature approaches the magnet, and consequently the levers are so arranged that the work done by them in overcoming the resistance of the spring is small at the beginning of their motion and increases as nearly as possible in exact proportion to the increase in the force of the magnetic attraction of the magnet for the armature as the parts are moved, the engaging surfaces 15 and 16 being shaped so as to cause this result to take place. A stop 27 is provided in position to be engaged by lever 11 to prevent the armature being moved away from the magnet more than a limited distance.

Electric current is supplied to the magnet from any suitable source of supply, such as a battery or dynamo, and is interrupted intermittently by any well-known device, so that the pole-pieces of the magnet are magnetized and demagnetized at intervals which when the apparatus is used as a clock are regular. Thus the armature is alternately drawn toward the magnet, withdrawing the pawl 21 against the tension of spring 17 and released upon the interruption of the current, which allows the spring then to project the pawl and turn the ratchet a distance of one tooth or more, according to the proportions of the parts, and at the same time withdraw the armature from the magnet.

By the construction and arrangement described I am enabled to employ a magnet of less power and a current of less quantity and force than is necessary where the driven mechanism is moved in direct proportion to the amount of movement of the armature for the reason that when the movement of the driven mechanism is of uniform amount throughout the force necessary to start the same must be at least as great as that necessary to continue its motion throughout its entire extent, and thus the increased pull exerted by the magnet as the armature approaches it is not used, but is simply wasted. With my apparatus, however, very little force is necessary to commence the move-

ment, and consequently a comparatively weak magnetic pull is sufficient to start the device, while by the time the greatest portion of the work must be accomplished the armature has moved so near the magnet that the attraction is strong enough to accomplish the work, and all of the energy provided is utilized. Evidently, therefore, the superior economy in the use of power which I obtain by my invention permits both economy of material in constructing the apparatus and economy in operation.

It is evident that the exact arrangement of the levers is not essential, since, if desired, the pivot of the lever which carries the armature may be at one end thereof and the levers may also be arranged so that the magnetic pull will actuate the lever 12 directly to turn the ratchet instead of to move it away from the ratchet so that a spring can move it on its operative stroke, the essential features being the construction of the levers by which the point of application of the force of the actuator upon the driven lever is shifted, so that the work performed increases proportionately to the increase of magnetic attraction as the armature approaches the poles of the magnet.

I claim—

1. In a magnetic motor, an electromagnet, an armature arranged to be moved by the attraction of the magnet, a lever connected to the armature, a member arranged for engagement and operation by said lever, said lever and member being so constructed and arranged that as the armature is moved and the force of the magnetic attraction upon it is varied, the amount of motion imparted to the said member by the lever is varied in proportion, and mechanism having connection with said member so as to be driven thereby with a step-by-step movement.

2. In a magnetic motor, an electromagnet, a lever, an armature for the magnet carried by said lever and adapted to be moved by the attraction of the magnet, a movable member adapted to be moved by said lever, the said lever and member being constructed and arranged so that the force of said lever is applied to said member at points at varying distances from the pivot of the lever as the distance between the magnet and armature is varied, mechanism movable step by step, and driving connections between said member and mechanism for intermittently operating the latter.

3. In a magnetic motor, an electromagnet, a lever, an armature for the magnet carried by said lever and adapted to be moved by the attraction of the magnet, driven mechanism movable step by step, a second lever, and intermittently-acting connections with said lever adapted to operate said mechanism, the said levers being arranged to engage each other, and one of said levers being

curved at its engaging surface to cause the point of engagement to shift as the armature is moved relatively to the magnet and the armature-carrying lever moved thereby.

4. In a magnetic motor, an electromagnet, a rotary driven member, a movable armature for the magnet, a lever having a reciprocating connection arranged for rotating said driven member, and a second lever connected to the armature, and arranged to engage and move said first lever, said levers being constructed and arranged so that as one is moved its point of engagement with the other is caused to shift so as to increase the amount of movement imparted to the other lever proportionately to the variations in the amount of the attraction of the magnet on the armature due to the varying distances between the magnet and armature.

5. In a magnetic motor, an electromagnet, a lever, an armature for the magnet carried by said lever and adapted to be moved by the attraction of the magnet, a rotary shaft, and a second lever having reciprocatory connections arranged to communicate rotary movement to said shaft, and being engaged with said first lever, the said first lever having its engaging side longitudinally curved so that as it is moved its point of engagement with the second lever is shifted to varying distances from its pivot to cause the force received therefrom by the second lever to vary inversely to the force of the magnetic attraction acting on the armature.

6. In a magnetic motor, an electromagnet, a lever, an armature for the magnet carried by said lever and adapted to be moved by the attraction of the magnet, a shaft, a ratchet mounted on the shaft, a second lever, and a pawl carried thereby and arranged to engage said ratchet, the second lever being engaged and operated by the first lever, and said levers being so constructed and arranged that they are caused to engage at points varying in distance from their pivots as the first lever is moved and the distance between the armature and magnet varied.

7. In a magnetic motor, an electromagnet, a lever, an armature for the magnet carried by said lever and adapted to be moved by the attraction of the magnet, a shaft, a ratchet mounted on the shaft, a second lever mounted for engagement and operation by the first-named lever, a pawl carried by said second lever and arranged to engage said ratchet intermittently, and a stationary pawl arranged to engage and hold the ratchet while the lever-carried pawl is out of engagement therewith.

8. In a magnetic motor, an electromagnet, a lever, an armature for the magnet carried by said lever and adapted to be moved by the attraction of the magnet, a shaft, a ratchet mounted on the shaft, a second lever mounted for engagement and operation by

the first-named lever, a pawl carried by said second lever and arranged to engage said ratchet intermittently, a stationary pawl arranged to engage and hold the ratchet while 5 the lever-carried pawl is out of engagement therewith, and means for engaging said pawls alternately.

9. In a magnetic motor, an electromagnet, a lever, an armature for the magnet carried 10 by said lever and adapted to be moved by the attraction of the magnet, a shaft, a ratchet mounted on the shaft, a second lever mounted for engagement and operation by the first-named lever, a pawl carried by said 15 second lever and arranged to engage said ratchet intermittently, and means located in the path of movement of said pawl arranged to be engaged by said pawl and to force and hold the same in positive engagement with 20 the teeth of the ratchet when the pawl is projected.

10. In a magnetic motor, an electromagnet, a lever, an armature for the magnet carried

by said lever and adapted to be moved by the attraction of the magnet, a shaft, a 25 ratchet mounted on the shaft, a second lever mounted for engagement and operation by the first-named lever, a pawl carried by said second lever and arranged to engage said ratchet intermittently, a stationary pawl arranged to engage and hold the ratchet while 30 the lever-carried pawl is out of engagement therewith, a device adapted to engage the lever-carried pawl to hold the same in engagement with the teeth of the ratchet when the 35 pawl is projected, and a member rigidly supported on one of the levers and adapted to engage and hold the stationary pawl in engagement with the teeth of the ratchet.

In testimony whereof I have affixed my 40 signature in presence of two witnesses.

MURRAY CHEEVER.
